UNITED STATES PATENT OFFICE.

COY MACMILLAN BUGBEE, OF SPRINGFIELD, VERMONT.

TONGUE-DEPRESSOR.

1,344,020.

Specification of Letters Patent. Patented June 22, 1920.

Application filed June 11, 1919. Serial No. 303,275.

To all whom it may concern:

Be it known that I, COY M. BUGBEE, a citizen of the United States, and a resident of Springfield, in the county of Windsor 5 and State of Vermont, have invented a new and Improved Tongue-Depressor, of which the following is a full, clear, and exact description.

My invention relates to tongue depressors 10 of a type suitable for use in surgery, dentistry, and related professions for the purpose of promoting accessibility to the interior of the human mouth.

More particularly stated my invention 15 comprehends a tongue depressor having such form that it may be made up inexpensively and used for depressing the tongue under such conditions that a thorough inspection can be made at any and all stages 20 of the use of the device.

My invention further contemplates giving such form to the tongue depressor that the operator in using it can depress the tongue to any desired extent by simply manipulating 25 the depressor by means of his fingers.

My invention contemplates various structural improvements in devices of this general character for the purpose of improving the efficiency of the same.

Reference is made to the accompanying 30 drawing forming a part of this specification and in which like reference letters indicate like parts in all the figures.

Figure 1 is a plan view of my improved 35 tongue depressor complete.

Fig. 2 is a side elevation of the same.

Fig. 3 is a side elevation showing the 40 tongue depressor as it appears when pressure is applied to it by the fingers of the operator during the use of the device.

A piece of spring wire 4 is bent as shown 45 in the figures and this is provided with wire loops 4^a. The spring wire is further provided with straight extending portions 5, 6 and 50 with a portion 7 bent upwardly and downwardly as indicated in Fig. 2 and carrying an eye 8. The portion 5 carries an upwardly extending portion 9 and mounted upon the latter is a blade 10 comparatively wide and having a large surface for engaging the tongue 55 as may be understood more particularly from Fig. 1.

The portions 5 and 6 are provided respectively with finger plates 11, 12 to be engaged by the fingers and thumb of the operator as indicated more particularly in Fig. 3.

The manner in which the device is used is illustrated in Fig. 3, the patient's tongue, chin and adjacent organic members being 60 indicated by dotted lines.

The operation of my device is as follows: The operator places his thumb and forefinger upon the plates 11 and 12, and by pressing these plates toward each other 65 causes eye 8 and the blade 10 to recede from each other, he then applies the device as indicated in Fig. 3, the blade 10 being placed upon the patient's tongue so as to extend backwardly toward the base thereof, 70 the eye 8 being placed against the underside of the patient's chin. The device is then released, and by its spring pressure it causes the blade 10 to depress the tongue and also to force it forwardly—that is toward the patient's front, as may be understood from Fig. 3. With the device thus applied the patient's tongue remains depressed and as far as practicable out of the operator's way 75 so that he can have a more favorable opportunity to work in the patient's mouth.

It will be noted that the device when once in position remains self-clamped, that is to say it holds itself in position and also holds the patient's tongue in suitable position for the purpose indicated. This enables the operator to use both of his hands for purposes of dentistry or other work relative to the patient's mouth.

I do not limit myself to the precise mechanism shown, as variations may be made therein without departure from the spirit of the invention.

Having thus described my invention, I claim as new, and desire to secure by Letters Patent:

1. A tongue depressor comprising a single piece of spring wire bent to form loops, and provided with portions crossing each other, each of said portions being provided 90 with a finger plate, one of said portions being bent to form a transversely extending eye for engaging a patient's chin, and the other of said portions being provided with a

flat member curved slightly in the general direction of its length.

2. A tongue depressor comprising a single piece of spring wire bent to form loops, and provided with portions crossing each other, each of said portions being provided with a finger plate, one of said portions be-

ing bent upwardly and then laterally to form a transversely extending eye for engaging a patient's chin, and the other of said portions being provided with a tongue engaging member curved slightly in the general direction of its length.

COY MACMILLAN BUGBEE.
